Patented July 18, 1916.

UNITED STATES PATENT OFFICE.

JOHN WATTS, OF KANSAS CITY, MISSOURI.

CHARGE-FORMING DEVICE FOR INTERNAL-COMBUSTION ENGINES.

1,191,488.

Specification of Letters Patent. Patented July 18, 1916.

Application filed June 21, 1913. Serial No. 775,019.

To all whom it may concern:

Be it known that I, JOHN WATTS, a citizen of the United States, residing at Kansas City, in the county of Jackson and State of Missouri, have invented certain new and useful Improvements in Charge-Forming Devices for Internal-Combustion Engines, of which the following is a specification.

This invention relates to charge forming devices for internal combustion engines, and my object is to provide in connection with this type of engine means for utilizing kerosene or other similar grades of liquid hydrocarbons as an efficient and satisfactory fuel for operating the engine. In carrying out this object, I have devised an apparatus for heating air by means of the exhaust gases of the engine and conducting the air so heated to a point adjacent the intake manifold where it is caused to vaporize the oil as the latter is fed into the engine.

With this general object in view, the invention consists in certain novel and peculiar features of construction and organization as hereinafter described and claimed; and in order that it may be fully understood reference is to be had to the accompanying drawing, in which—

Figure 1, is a side elevation, partly in section, of the engine of an automobile and the exhaust manifold thereof with my improved means applied thereto. Fig. 2, is a vertical section through the thermostat element, and Fig. 3, is a section on the line III—III of Fig. 1, these sections being on enlarged scales. Fig. 4, is a section on the line IV—IV of Fig. 2.

Referring to the drawing, the cylinders 2 of the engine are provided with the usual intake manifold 4 and exhaust manifold 6. In a portion of the exhaust manifold is coiled a pipe 8 so as to subject the same to the heating action of the exhaust gases. For supplying air to this pipe 8, a rotary pump 10 is provided and adapted to be driven from the cam shaft 12 of the engine. This pump is of the positive action type, comprising the rotary disk 14 mounted on said shaft and centrifugal sliding blades 16 adapted to take air from the inlet opening 18 and force the same through the pipe 20, which conducts air to the pipe 8. This pump is so constructed that its pulsations will be properly timed to the piston movements of the different engine cylinders.

The heated air is led away from the coil

8 through a pipe 22 in which is located a thermostat 24 of a wellknown type for regulating the admittance of air into the pipe 22, as required to maintain the air below a given temperature. This thermostat comprises a chamber 26 provided with a sensitive temperature-change recording element in the form of a diaphragm chamber 28 containing alcohol 30, or other suitable thermometric liquid, the degree of sensitiveness of which element may be regulated by means of a screw 32. The recording element is connected by a rod 34 with one arm of a bell crank 36 which is pivoted upon the thermostat. The other arm of the bell crank is connected by a link 38 with an extension 40 to a sleeve 42, the purpose of which is to act as a valve for regulating the admittance of air into the pipe 22 through the opening 44 therein, the movement of the sleeve being controlled by the movements of the diaphragm 28 transmitted through the rod 34, bell crank 36 and link 38. To insure a supply of external air to pipe 22, through opening 44 when the same is uncovered by sleeve 42, the pipe 22 is provided internally with a nozzle or reduced portion 45 which extends across the opening 44, to produce an injecting action on the outside air. From the chamber 28 the heated air enters an injector 46 which discharges into the intake manifold 4. An oil feed pipe 48 connects the injector with the float chamber 50 which surrounds the injector and provides an air intake opening 52 around the latter. Within the float chamber is mounted the usual float 56 which operates a needle valve 58, controlling communication with the oil supply pipe 60 communicating with the reservoir, not shown, for containing kerosene or a similar grade of liquid hydrocarbon. A check-valve 62 regulates the supply of auxiliary air. For starting purposes, gasoline will be drawn from a tank 64 which communicates through a pipe 66 with the intake of the pump 10, from where it follows the path described into the intake manifold.

In operation, assuming that the engine has been started, the pump driven by means of the cam shaft 12 forces air through the coil 8 where it is heated by the hot exhaust gases from the engine. From there the heated air is driven through the thermostat to the injector. The thermostat is set to operate the valve 42 to admit additional air whenever the air from the coil is heated

above a given temperature, so that no air above that temperature will be allowed to mix with the oil at the injector thereby guarding against supplying any air to the 5 injector that will be hot enough to ignite the oil. The air passes forcibly through the injector under the driving action of the pump, and oil is drawn out through the pipe 48 under the combined action of the injector 10 and the suction of the engine. The oil is thereby completely broken up and vaporized by the hot air and discharged into the intake manifold along with whatever additional air is sucked through the intake opening 15 52.

It will thus be seen that I have produced a very simple and effective apparatus for vaporizing the liquid fuel used by means of the heat of the exhaust and that this means 20 may be safely employed when arranged as described without any danger of exceeding a given temperature at the injector, since the apparatus is self regulating in this respect.

25 While I have illustrated the preferred mode of carrying out my invention, it is to be understood that I do not limit myself thereto, but reserve the right to all changes falling within the spirit and scope of the 30 appended claims.

I claim—

1. In an internal combustion engine, the combination with the intake and exhaust conduits, an air-pipe passing through a portion 35 of the exhaust conduit and communicating with the intake conduit, said pipe

having an opening intermediate the exhaust and intake conduits, and a sliding sleeve controlling passage through said opening, a thermostat in said pipe between said opening and the intake conduit, and connections between said thermostat and sleeve for operating the latter to admit air into said pipe for maintaining the temperature of the air supplied to the intake conduit below a given 45 point.

2. In a charge forming device for internal combustion engines, the combination with the intake and exhaust conduits, of a liquid fuel supply communicating with the intake 50 conduit, an air-pipe passing through a portion of the exhaust conduit and communicating with the intake conduit at the point where said liquid-fuel supply communicates therewith, said pipe having an air inlet 55 opening intermediate the exhaust and intake conduits and a valve controlling passage through said opening, a thermostat located in said pipe between said opening and the intake conduit, and connections between said thermostat and valve for operating the latter to admit air into said pipe for maintaining the temperature of the air supplied to the intake conduit below a given 60 point.

65 In testimony whereof, I affix my signature, in the presence of two witnesses.

JOHN WATTS.
